US0D1042104S

(12) **United States Design Patent** (10) **Patent No.:** **US D1,042,104 S**
(45) **Date of Patent:** **** Sep. 17, 2024**

(54) **HELICAL PILE**

(71) Applicant: **Daiye Screw Pile LTD.**, Taipei (TW)

(72) Inventor: **Jen Te Yang**, Taipei (TW)

(73) Assignee: **DAIYE SCREW PILE LTD.**, Taipei (TW)

(**) Term: **15 Years**

(21) Appl. No.: **29/839,733**

(22) Filed: **May 24, 2022**

(51) LOC (14) Cl. **08-08**

(52) U.S. Cl.

(57) **CLAIM**

The ornamental design for a helical pile, as shown and described.

DESCRIPTION

FIG. 1 is a perspective view of helical pile according to the present design;

FIG. 2 is a front view of the helical pile according to the present design;

FIG. 3 is a rear view of the helical pile according to the present design;

FIG. 4 is a top view of the helical pile according to the present design;

FIG. 5 is a bottom view of the helical pile according to the present design;

FIG. 6 is a right-side view of the helical pile according to the present design; and,

FIG. 7 is a left-side view of the helical pile according to the present design.

The broken lines represent environment and form no part of the claimed design.

1 Claim, 7 Drawing Sheets
